UNITED STATES PATENT OFFICE.

THOMAS SWAIM ARMSTRONG, OF NORTH PLAINFIELD, NEW JERSEY.

COOLING APPLIANCE.

SPECIFICATION forming part of Letters Patent No. 700,005, dated May 13, 1902.

Application filed November 19, 1901. Serial No. 82,894. (No model.)

To all whom it may concern:

Be it known that I, THOMAS SWAIM ARMSTRONG, residing at North Plainfield, in the county of Somerset and State of New Jersey, 5 have invented a new and Improved Cooling Appliance, of which the following is a specification.

This invention is in the nature of an improved appliance for cooling grape-juice and 10 other like beverages, and primarily has for its object to provide a cooler for such purpose of a very simple and economical construction which can be readily handled and placed in an operative condition and which will effectively serve for its intended purposes. 15

My invention in its generic nature comprehends a novel means for properly supporting the container or beverage-holding can within the cooling vessel or jacket clear from sides 20 or bottom of the cooling vessel and an improved construction of drawing-off tube cooperatively arranged with the jacket and container whereby to permit of a quick and convenient removal of the container from the 25 cooling vessel or placing the same therein as conditions may make necessary.

In its complete make-up my invention also includes a peculiar construction of brackets adjustably and detachably held within the 30 cooling-jacket for properly supporting and bracing the upper end of the container, and in its subordinate features my invention consists in certain details of construction and peculiar combination of parts, all of which 35 will hereinafter be fully described, and particularly pointed out in the appended claims, reference being had to the accompanying drawings, in which—

Figure 1 is a perspective view of my invention. Fig. 2 is a vertical section of the same, the parts being shown in their normal or operative position. Fig. 3 is a similar view illustrating the manner of removing the container from the cooling-jacket. Fig. 4 is a horizontal section taken on the line 4-4 of Fig. 2. Fig. 5 is a similar view on the line 5-5 of Fig. 2.

My invention in its general characteristics embodies an external vessel or jacket for holding the cooling agent, open at the top and 5 having a closure member for the said opening, and a container (in which the beverage to be cooled is held) adapted to be supported upon

the bottom of the cooling vessel immersed in the ice or other cooling agent, and so far as it relates to the general construction of my invention the same involves no new principle, as the essential features thereof lie in the peculiar manner in which the holder of the container is detachably supported within the cooling-chamber, the manner in which the 6c drawing-off spigot is connected therewith, and the bracket devices for sustaining the upper and lower ends of the holder. 55

Referring now to the accompanying drawings, in which like characters indicate like parts in all the figures, 1 indicates the cooling vessel, which may be of any desired size—for example, that of the ordinary water-cooler. This vessel is preferably made of galvanized iron, with inner and outer walls *a b*, both at 70 the sides and bottom, to form a surrounding space for the reception of charcoal or other non-conducting substance. At the top the vessel has an opening *c*, normally held closed by a charcoal-packed closure member 2, as 75 shown. At the lower end the vessel 1 has a drawing-faucet 3 for drawing off the water.

In horizontal section the vessel 1 may be round, square, or of other desired shape, and centrally on the bottom thereof is fixedly held 80 a collar or ring 4, that projects up a short distance, as clearly shown in Fig. 2, by reference to which it will be noticed the diameter of the said collar 4 is just sufficient to permit the lower end of the container 5 fitting therebetween. 85

The container 5 may be formed of any material suitable for the purpose—for example, granite-ware—and the same is of less height than the cooling vessel to permit of the ice 90 or other cooling agent passing over the top thereof, and to provide for a maximum cooling effect on the bottom, said container has three, more or less, galvanized-iron brackets 6 6, which project downward below the bottom sufficiently to hold the bottom of the container from contact with the bottom of the vessel 1, and to further augment the cooling action the collar 4 may be perforated, as indicated in the drawings, to allow for a free 95 circulation of the cooling agent under the container. The container has a closure member 5^a at the top, and the upper end of the said container in practice is braced and properly 100

supported by brackets projected radially inward from the inner face of the vessel 1. In the practical arrangement of my invention I employ three of the said brackets, and each 5 of the brackets is formed of pieces of metal—or galvanized iron, for example—bent up in a V shape, with their ends terminating in foot portions 7^a, and two of the said brackets are fixedly held by riveting or otherwise securing 10 the foot portions to the inner wall of the vessel, as shown in the drawings. The third bracket (indicated by 7^x) is disposed directly over the drawing-off faucet, through which the beverage from the can passes, and the 15 said bracket is detachably held in position, and for such purpose its foot portions 7^a are bent laterally to engage with the flanges 8, secured upon the inner side of the vessel 1. In practice the foot portions of the brackets 20 7^x are sprung into engagement with the flanges 8, and by frictional contact therewith the said bracket is held in a proper position. It will thus be seen that by providing a collar at the bottom and the brackets at the top 25 the container will be properly held centrally within the cooling vessel 1.

The lower end of the container is provided with an opening 5^c (see Fig. 3) of sufficient diameter to permit the said end moving laterally over the inner end of a drawing-off 30 tube 9, made of hard rubber. This tube is threaded externally nearly its entire length, and one end of the same is adapted to extend into and pass through the opening 1^d in the 35 wall of the vessel 1, as best shown in Figs. 2 and 4, and to provide for a fluid-tight joint at the point where the said tube 8 enters the wall of the vessel 1 a soft-rubber washer 10 is fitted thereover, which is tightly clamped 40 in position by a hard-rubber nut 11^a. The outer end of the drawing-off tube 9 is externally threaded to receive the threaded shank of the hard-rubber drawing-off faucet 11^x, as 45 shown, and the said externally-threaded tube is made of a size sufficiently long, so that when 50 the container is set centrally within the vessel 1 the inner end of the tube 9 will project slightly inside of the container, and to provide for a fluid-tight joining of the lower end 55 of the container with the said externally-threaded tube I provide a hard-rubber nut 12^a, adapted to fit the inner end of the tube 9, and a jam-nut 13, fitted on the tube externally of the container, soft-rubber washers 12^a 13^a being used to provide for a fluid-tight joint.

From the foregoing description, taken in connection with the accompanying drawings, it is thought the manner in which my cooling 60 appliance operates will be readily understood. It will be noticed that the contents of the container may be readily drawn off through the faucet 11^x, and to remove the container from the cooler it is only necessary to unscrew the rubber nut 11^a upon the inside of 65 the container, and by then detaching the bracket, or rather sliding it up sufficiently

high to a point above the top of the container, and by slightly tipping the container toward the outward side of the vessel the same may 70 be readily released from the collar 4 and from engagement with the inner end of the tube 9 and drawn out of the vessel, it being manifest that to reinsert the container it is only necessary to fit the lower end thereof over 75 the inner end of the tube 9 and properly adjust the nuts and washers 11^a 12^a 13 13^a and the brackets 7^x, when the appliance will be again in position for a proper operation.

Having thus described my invention, what 80 I claim, and desire to secure by Letters Patent, is—

1. In a cooling appliance of the character described, the combination with the vessel for holding the cooling agent, said vessel being 85 open at the top and having a drawing-off tube at the bottom whose inner end projects inward toward the center of the vessel and having a collar projected up from the bottom thereof; of a retainer or beverage-holder, said 90 holder having pendent supporting-brackets at the bottom and having its lower end of a size to fit within the upper edge of the collar on the bottom of the vessel, the brackets projected radially inward from the upper end of 95 the vessel adapted to engage the upper end of the said container or holder, one of said brackets being detachably held, the container or holder having an opening at the lower end, whereby it can be slipped onto the inner end 100 of the drawing-off tube, and the clamping-nuts for securing the tube and the container all being arranged substantially as shown and for the purposes described.

2. In a cooling appliance of the character 105 described, the combination with the vessel for holding the cooling agent, said vessel having a draining-faucet and having a drawing-off tube whose inner end projects toward the center of the vessel, said projecting end being 110 threaded, said vessel having an annular collar projected upward from its bottom, and a series of brackets projected radially inward from the upper end of the vessel, one of said 115 brackets being disposed over the drawing-off tube and detachably held within the vessel; of the container or holder, said holder having pendent brackets at the lower end and having the said end of a diameter to fit between the upper edge of the collar at the bottom of 120 the vessel, the lower end of the said holder being open, whereby it can be readily fitted over the projecting end of the drawing-off tube, clamping-nuts engaging the said tube for holding the container or holder in a fluid-tight engagement with the tube, all being arranged substantially as shown, whereby by 125 releasing the nuts from the drawing-off tube, and removing the detachable bracket, the container or holder can be tilted and slipped from 130 engagement with the inner end of the drawing-off tube, substantially as shown and for the purposes described.

3. The hereinbefore - described improve-

ment in cooling appliances, comprising a vessel adapted to hold the cooling agent, said vessel having an annular collar projecting vertically upward from the bottom and having a plurality of brackets projected radially inward, said brackets being fixedly connected to the interior of the vessel; another bracket of like structure projected radially in line with the other brackets, said bracket being detachably connected with the inner side of the vessel, an externally-threaded drawing-off tube, one end of which projects through the vessel and has an internally-threaded outer end, the inner end of said tube projecting inward to a point over the collar on the bottom of the vessel, said end being threaded, the container having pendent bracket members adapted to straddle the collar on the bottom of

the vessel, said vessel-bottom being arranged to fit within the upper end of the collar, the upper end of said vessel projecting above the brackets, said brackets and the container being relatively of such proportions that the brackets will form lateral braces for the said container, the container having an elongated opening at the lower end, whereby it can be fitted over the inner end of the externally-threaded offtake-tube, and the nuts and washers for effecting a tight adjustment of the container, the vessel, and the offtake-tube, all being arranged substantially as shown and for the purposes described.
